UNITED STATES PATENT OFFICE.

ALEXANDER M. GOW, OF DULUTH, MINNESOTA.

GAS-PRODUCER.

1,272,252.

Specification of Letters Patent.

Patented July 9, 1918.

Application filed December 20, 1917. Serial No. 208,079.

To all whom it may concern:

Be it known that I, ALEXANDER M. Gow, a citizen of the United States, and resident of Duluth, in the county of St. Louis and 5 State of Minnesota, have invented certain new and useful Improvements in Gas-Producers, of which the following is a specification.

This invention relates to gas producers. 10 One of the objects of my invention is to automatically feed fuel uniformly and maintain the fuel bed in the best possible condition.

Another object of my invention is to 15 maintain the fuel in the coking zone uniformly porous and open.

Another object of my invention is to feed 20 and mechanically distribute the fuel continuously and uniformly over the entire surface of the fuel body at any desired rate of speed.

Another object is to provide a gas producer adapted to meet all the requirements for successful commercial operation.

Generally speaking, these and other objects are accomplished by providing, in 25 combination, a gas producing chamber, means for feeding and distributing fuel in said chamber, and means whereby the fuel 30 is maintained in a uniformly porous and open condition.

The invention is illustrated on the accompanying sheet of drawings, in which—

Figure 1 is a sectional view of a gas producer constructed in accordance with my invention, some of the parts being shown in 35 elevation; and

Fig. 2 is a similar view taken at right angles to the one shown in Fig. 1.

The various novel features of my invention will be apparent from the following 40 description and drawings and will be particularly pointed out in the appended claims.

When a caking, bituminous coal is fed to a producer, the heavy hydrocarbon gases and tar vapors are first given off. The fuel becomes soft and sticky, offering considerable resistance to the passage of air and 45 steam admitted below. As the fuel descends it is progressively coked. Below this coking zone the fuel is consumed or gasified. Below the zone of combustion or gasification lies the ash zone, wherein the fuel content

is relatively very low. Of course, these 55 three zones are not sharply separated. For the proper operation of a producer the fuel bed should descend uniformly and offer uniform resistance to the blast. It is well known that if coke or a semi-bituminous 60 non-caking coal is used, little trouble is experienced from irregular combustion of the fuel bed and little poking is required. With a caking, bituminous coal, however, there is a great tendency for the blast to "wander," 65 resulting in irregular consumption of fuel, holes in the fuel bed, hard spots in the fire, high fuel bed on one side and low on the other, and irregularity in the quality of the gas. To correct these conditions it is necessary to either poke the fuel bed by hand, or resort to some mechanical poking or stirring device.

To this end I propose to chop the fuel in 70 the coking zone by means of a vertically-acting water-cooled chopper. This chopper prevents the coking particles of coal from agglomerating; it reduces the resistance within the coking zone to the passage 75 of the blast, and maintains the top of the fuel bed uniform and homogeneous. In addition, the chopping arm may be revolved and used to level the surface of the fuel at any desired height within the range of the mechanism. As stated above, I have also 80 proposed to provide a feeding arrangement which shall mechanically distribute the fuel continuously and uniformly over the entire 85 surface of the fuel body at any desired rate of speed.

After removing a quantity of ash from 90 the bottom of the producer, it is desirable that the fuel bed be broken down. The vertically-acting chopper serves this purpose, inasmuch as it is capable of vertical 95 and rotary motion at any desired speed.

Referring particularly to the drawings, it will be noted that I have provided a gas producer 10 having a gas producing chamber 11 provided with a top 12 which is 100 mounted for rotation, the outer end of the cover 12 being in the form of a gear 13 which may be actuated by any suitable pinion 14 meshing therewith, the pinion being driven from any suitable source. Suitably 105 supported channel irons 15 are provided, to which are secured guide castings 16 in which is movably mounted a frame 16^a, to which

is connected a cylinder 17 having laterally extending arms 18, to which are connected the rods 19 of pistons which operate in cylinders 20. To the piston which works in the cylinder 17 is connected a piston rod 23, to the lower end of which is connected a poker 24, carrying at its lower end a chopper arm 25. Secured to the upper end of the poker 24 is a ratchet wheel 26, which, 5 when the poker and chopper arm are raised, moves into engagement with the pawls 27 pivotally mounted upon the frame 16^a. It is apparent that as the ratchet wheel continues to move upwardly after it engages the 10 pawls 27 the ratchet wheel, and with it the poker 24 and chopper arm 25, will be forced to rotate a predetermined amount commensurate with the amount of rising movement of the ratchet wheel. The fluid supply to 15 the piston 17 is controlled by a valve 28, which preferably is continuously rotated by any suitable means to permit the passage of fluid into the cylinder 17 to cause an upward movement of the piston and therefore the 20 chopper arm 25, and then to permit the fluid to escape through connection 29 as the piston and therefore the chopper arm lower due to their own weight. The upper part 25 of the cylinder 17 is provided with a vent 30. Due to the fact that the bed of coal in 30 the gas producing chamber 11 varies in height, it is necessary that the chopper arm in its lowest position of adjustment be adjustable with its cylinder 17 while still maintaining the same effective stroke of the 35 chopper. This is accomplished by raising the cylinder 17, poker 24 and chopper 25 as a unit by regulating the fluid controlled valve 31 to permit a supply of fluid pressure to enter the lower end of the cylinders 20, whereupon the parts in question will be raised. It will be appreciated also that the parts in question may be lowered, and, as a matter of fact, adjusted to any position 40 and retained there in accordance with demands.

Carried by the cover 12 is a hopper 32 for the reception of coal, the lower end of the hopper extending through an opening 50 33 in the cover 12. The opening 34 in the lower end of the hopper 32 is regulated by a distributor 35 mounted upon one end of a shaft 36, upon the other end of which is splined a gear 37 meshing with a gear 38 secured to the guide members 16^a. A lever 55 39 connected to the shaft 36 regulates the extent of the opening 34, and therefore the amount of fuel which is supplied automatically to the gas producing chamber 11. It 60 will be understood that as the top 12 of the gas producer is rotated, the coal hopper 32 will be moved in a circle. Due to the fact that the gear 38 is stationary, the distributor 65 will be given a rotary movement, the coal being mechanically distributed continuously

and uniformly over the entire surface of the coal body, and, as a matter of fact, at any desired rate of speed. Water for cooling purposes is passed into the inlet pipe 40, which is conveyed through the hollow poker 71 24 and chopper 25 by pipe 41, which terminates in the chopper 25. The water overflows through an outlet 42 in the upper part of the poker 24 and passes downwardly into a pipe 43 extending around the poker 24 75 and downwardly between the pipe 43 and pipe 44, and upwardly between pipe 44 and pipe 45. The intermediate pipe 44 is held stationary while the pipes 43 and 44 rotate with the top of the gas producer. In this 80 way the parts in question are effectively cooled. The water in the pipes 43, 44 and 45 serves to provide a water-seal.

In operation, a fuel bed having been established in chamber 11 to a desired height, 85 valve 28 is actuated, causing the piston and cylinder 17 to travel upward, lifting the chopper 25 out of the fuel bed. At the upper end of the stroke the pawls 27 engage the ratchet wheel 26 and produce a partial 90 revolution of the poker 24, thus revolving chopper 25 above the fuel bed. As valve 28 revolves, the steam or air, or any other fluid, is released from under the piston, and the poker 24 and chopper 25 fall by gravity 95 and descend into the fuel bed an amount depending upon the weight of the moving parts and the resistance offered by the fuel. It will be observed that I do not drive the chopper down by pressure, but allow it to 100 fall by gravity. It is not my desire to ram the surface of the fire. It is obvious that the weight of the reciprocating parts can be counterbalanced so that any desired chopping blow may be delivered. In the event 105 that the chopper 25 meets undue resistance it does not force itself into the fire. The continued revolution of valve 28 causes the reciprocation of the poker 24, while at each upward stroke when the chopper arm 25 is 110 above the fire a partial rotation is given to the parts, the result being that the entire surface of the fuel bed receives the chopping action.

The chopping arm may be given a variety 115 of shapes. However, the lower end of the chopper arm is sharp and in cross section it is wedge-shaped and preferably is fabricated from sheet steel welded at the joints. The height of the fuel in a gas producer necessarily is variable. By means of the cylinders 20 controlled by the valve 31 the chopper arm 25 may be actuated at various levels, depending on the level of the fuel in the producer.

As the producer top 12 revolves it carries with it the hopper 32. The distributor 35 revolves and the fuel in the hopper is uniformly distributed, the rapidity of feed being determined by the opening between the 130

distributer 35 and the bottom of the hopper 32, which opening is determined by means of the lever 39.

If desired, the chopper 25 may be 5 revolved manually by inserting a suitable wrench in any one of the openings 46 in the ratchet wheel 26, giving the latter a turning movement. It is obvious that various mechanisms may be provided which are 10 capable of raising and lowering the poker 24 and chopper arm 25 and revolving the same at the upper end of the stroke. It is also obvious that the functions performed by cylinders in determining the operative 15 height of the chopper in the producer can be performed by means of screws or levers, or other mechanism. In fact, there may be various modifications of the invention herein particularly shown and described, 20 and it is my intention to cover all such modifications which do not involve a departure from the spirit and scope of the invention as set forth in the following claims.

What I claim is:

1. In combination, a gas producing chamber, means for distributing fuel in said chamber, and reciprocatory and rotary means whereby the fuel in the coking zone is maintained in a uniformly porous condition, the reciprocatory and rotary actions taking place at different times.

2. In combination, a gas producing chamber, and means whereby the fuel in said chamber may be disturbed by a vertical 35 movement throughout the whole surface of the fuel during a complete revolution of said means.

3. In combination, a gas producing chamber, a chopper mounted therein for a vertical movement to disturb the fuel in the chamber, and means for rotating said chopper only above the surface of the fuel in said chamber whereby different portions of the fuel may be disturbed.

4. In combination, a gas producing chamber, a chopper mounted therein for distributing the fuel in a vertical direction, and means for automatically rotating said chopper only after the same has been moved out 45 of engagement with the fuel.

5. In combination, a gas producing chamber, a vertically arranged shaft, a trans- 50 verse chopper mounted thereon, means whereby the vertical shaft may be raised

and lowered, and means whereby it may be given a partial revolution only when the chopper is above the fuel bed.

6. In combination, a gas producing chamber, a hollow vertical shaft, a hollow transverse chopper, means for supplying a cooling medium thereto, means whereby the vertical shaft and chopper may be raised and lowered, and means whereby they may be given a partial revolution only when the chopper is above the fuel bed. 65

7. The method of maintaining a uniform condition of the fuel in the top of a gas producer which consists in chopping the fuel to a predetermined depth, raising the chopper above the fuel, and giving the chopper a partial revolution only when in a raised position. 70

8. In combination, a gas producing chamber, a vertical shaft, a transverse chopper carried thereby, fluid actuated means for raising the vertical shaft and chopper, and means for giving the shaft and chopper a partial rotation only when the chopper is in a raised position. 75

9. In combination, a gas producing chamber, a vertical shaft carrying a transverse chopper, fluid actuated means for raising the vertical shaft and chopper, and fluid actuated means for adjusting the operative position of said first mentioned means. 80

10. In combination, a gas producing chamber, a vertical shaft carrying a transverse chopper, means for adjusting the height of the chopper relative to the fuel bed in the producer, said chopper also being movable into the coking zone for disturbing fuel therein, and means whereby the vertical shaft may be rotated for causing the chopper to level the fuel bed within the producer. 85

11. In combination, a gas producing chamber, a chopper mounted therein for disturbing the fuel in the coking zone, means for adjusting the height of the chopper relative to the fuel bed, and means 100 whereby the chopper may be rotated for leveling the fuel bed within the producer.

Signed at Duluth, Minnesota, this 17th day of December, A. D. 1917.

ALEXANDER M. GOW.
